METHOD OF MAKING SHAPED COAT HANGERS
William F. Deknatel, Chicago, and John C. Handzel, Des
Plaines, Ill., assignors to The Setwell Company, Chi
cago, Ill., a corporation of Illinois

Filed June 22, 1962, Ser. No. 204,414

9 Claims. (Cl. 144—326)

This invention relates to an improved method for making shaped wooden coat hangers.

Wooden coat hangers are of two types. In one, referred to as the ordinary type, the thickness (front to back dimension) is substantially uniform. In the other, it is not uniform, and the shape is characterized by an enlarged portion at the end of each arm, which can be referred to as the shoulder pad. This is the shaped type of coat hanger and is considered to be more preferable since, with respect to men's coats, the shoulder pad of the hanger prevents a creasing or deformation of the shoulder of the coat. More particularly, men's garments sometimes have a built up shoulder and this will tend to slide to one side or the other end of the ordinary type of coat hanger, whereas in the shaped type, the built up shoulder of the garment will more or less center itself on the shoulder pad of the hanger.

In the fabrication of hangers of both types, it is customary to take a block of wood, the cross section of which is rectangular, and to cut it along its broad surfaces into two complementary parts referred to herein as "block halves" which can be rearranged in a certain manner so that certain end surfaces are abutting, thus to provide the characteristic coat hanger shape with a built up neck. For purposes of reference, the under surface of the coat hanger, which is usually in the form of two plane surfaces, can be referred to as the dihedral angle of the hanger.

In the prior art method above described the dihedral angle surfaces of the hanger represent the narrow surfaces of the original rectangular block.

From the foregoing it will be seen that when a shaped coat hanger is made according to the prior art reference, the thickness of the block must be at least as great as the thickness of the shoulder pads. This represents a considerable waste of material since the remainder of the coat hanger is much thinner which means that much more than 50% of the wood of the original block is carved away as waste.

According to our method, a shaped coat hanger can be made with much less waste. The characteristic of our invention is that the shaped coat hanger is cut from a block in such a manner that the dihedral angle of the hanger represents the broad surfaces of the block. The block is of considerably less height than in the prior art method, and this represents the saving in material which is provided by our invention. The cut is referred to herein as the "block cut," and is made at an angle much less than 90° to the broad surfaces.

According to our invention, by making the line of the block cut not orthogonal to the broad surfaces as in the prior art, but at an angle thereto, then the cross section of each complementary block half is either triangular or trapezoidal, whereas according to the prior art method, the corresponding cross section is rectangular. This angle is much less than 90°, and preferably is from 10° to 45°.

By thus cutting the block on the bias, as it were, we have found that the characteristic configuration of a shaped type of coat hanger can be provided with very little waste of material.

With reference now to the drawings in which like reference numerals designate like parts:

FIGS. 1a, 1b and 1c show the original block in side, end and top views respectively;

2

FIG. 2 shows the block of FIG. 1 in a different position; FIGS. 3 and 4 are sections taken along lines 3—3 and 4—4 of FIG. 2 respectively, after the block has been cut into two halves;

5 FIG. 5 is a view showing the two complementary halves in a rearranged position;

FIG. 6 is a left end view of one of the halves;

FIG. 7 is a view similar to FIG. 5, but showing a further rearrangement of the halves;

10 FIG. 8 is a view similar to FIG. 7 but showing a further rearrangement of the parts;

FIG. 9 is a plan view of FIG. 8 showing the final shape in broken lines;

FIGS. 10, 11 and 12 are side elevation, plan and end views, respectively, of the finished hanger;

15 FIG. 13 is a view similar to FIG. 2 showing another example of my improved method;

FIG. 14 is a section taken along the line 14—14 of FIG. 13;

20 FIG. 15 is a plan view of the finished hanger made from the block of FIGS. 13 and 14; and

FIG. 16 is a section taken along line 16—16 of FIG. 15.

With reference now to FIGS. 1a, 1b and 1c, the block

25 10 is an elongate parallelepiped of rectangular cross section having oblique end surfaces 11 and 12. The side surfaces of the block, for purposes of further reference, will be referred to as the broad surfaces 20 and 21, and the narrow surfaces 22 and 23. If the block 10 is rotated through the angle theta of FIG. 1b, then the pro

30 jection will be as shown in FIG. 2. The curved line 13 in FIG. 2 is the line of a block cut which is parallel to the line of sight and perpendicular to the plane of projection. After the block has been cut, the relationship of the block cut 13 to the two complementary block

35 halves 14 and 15 is shown in FIGS. 3 and 4. Thus, the block cut 13 divides the block into two block halves each of which have curved surfaces 16 and 17 respectively. These surfaces are cylindrical surfaces, in the generic sense of the term, the elements of which are all disposed

40 at the angle theta to the broad surfaces 20, 21.

FIG. 5 is a projection in which the parts 14 and 15 are in the same angular disposition as shown in FIG. 2, and in which the axial alignment is maintained; however, the two block halves 14 and 15 have been offset axially.

45 FIG. 7 shows the two block halves 14 and 15 in axial alignment, but the block half 15 has been rotated 180° about its longitudinal axis, and has been moved up toward block half 14 so that one corner of the oblique end surface 11 touches one corner of the oblique end surface 12.

50 50 At this point, the two block halves 14 and 15 are each rotated about the point of contact so that the oblique surfaces 11 and 12 will be in full surface contact. In this position, the parts appear as shown in FIG. 8, when viewed in side elevation, and in FIG. 9 when viewed in plan. The projections of FIGS. 8 and 9 are orthogonal with respect to the abutting end surfaces 11 and 12.

55 In FIG. 2, the cut line 13 divides the broad surface 21 into two parts 21' and 21'', and the same applies to surface 20. These surface parts are identified in FIGS. 8 and 9; the parts 20'' and 21'' form the dihedral angle of the coat hanger.

60 Similarly, the inner neck surface parts 22' and 23' of FIG. 9 are parts of the surfaces 22 and 23 of the original block.

65 65 If it be assumed that the two halves 14 and 15 are glued or otherwise secured to each other along the abutting end surfaces 11 and 12, it will be seen that the assembly of FIGS. 8 and 9 approximates the distinctive configuration of a shaped coat hanger. In FIG. 9, the broken lines 24 indicate the manner in which the assembly can be carved away to produce the finished article.

In other words, the broken lines of FIG. 9 represent a shaped hanger in plan view, and the broken line outline conforms generally to the finished coat hanger shown in FIGS. 10, 11 and 12.

In the fabrication of the coat hanger 25, the separate block halves 14, 15 are individually shaped by several shaping cuts to more or less the final configuration; then glued or dowled together, then rough sanded, and then finally finish sanded to produce the final article 25 of FIGS. 10 to 12.

When the usual hook 28, shown in broken lines in FIG. 12, is attached to the wooden body 25, the coat hanger will hang freely, as shown in FIG. 12 by the broken lines 26; in other words, the center of gravity is located forwardly of the inner surfaces of the neck portion 27 with the result that the hanger tips forwardly somewhat.

This arrangement is the result of providing end surfaces 11, 12 which are oblique both with respect to the broad surfaces 20, 21 and with respect to the narrow surfaces 22, 23. In the two examples shown, the obliquity with respect to one block axis is substantially equal to the obliquity with respect to the other, and in both examples, the angle between the end surface and a side surface is about 65° to 70°.

In other words, the obliquity is about 20° to 25° with respect to each transverse axis making a total obliquity of from 30° to 35°. Thus, when the hanger is free hanging, the arms are disposed at about 110° to 120° to each other. When the hanger is thus permitted to hang so that the arm axis angle is in a substantially vertical plane, the "shaped" impression is considerably accentuated.

The invention is applicable to a wide variety of designs; FIGS. 13 and 14 are views corresponding to FIGS. 2 and 3, and show a block 30 of different proportions, and FIG. 15 is a plan view of a finished coat hanger 31 made from the block 30 of FIG. 13.

FIG. 16 shows that the vertical dimension of the neck portion 32 corresponds to the vertical dimension of the original block 30.

According to our invention the block cut 13 of FIG. 2, or 33 of FIG. 13, is made at an acute angle to the broad surface, whereas heretofore, it was made perpendicular to the broad surface. According to the present invention, the block cut will intercept all four surfaces of the block. However, in FIG. 2, in which the block is made at an angle of approximately 15° to the broad surface, the block cut extends primarily from one narrow surface 22 to the other, 23. In FIG. 13, in which the proportions of the block are considerably different, and in which the angle theta of the block cut is substantially 40° to the broad surface, the block cut 33 extends primarily from one broad surface to the other.

In other words, the orthogonal projection of the curved surface, which refers to a projection which is taken in the direction of its elements, will primarily fall on the narrow surface in the FIG. 2 modification, and will fall primarily on the broad surface of the FIG. 13 modification. With respect to the longitudinal axis of the block, the curve surface itself will be symmetrical so that the dimensions of the block halves are the same. However, the orthogonal projection of the curved surface upon either a broad or narrow side surface will be asymmetrical with respect to the longitudinal center line of said surface.

The angle theta referred to is the angle between the elements of the cylindrical surface 16 or 17 and the

plane of one of the broad surfaces, and preferably ranges from about 10° up to 45° or 60°.

Comparable results are obtained where the elements of the cylindrical surface 16, 17 are somewhat skewed with respect to a right section of the original block 10.

Although only preferred embodiments of our invention are shown herein, it will be understood that various modifications and changes in the method and construction shown may be made without departing from the spirit of our invention as pointed out in the appended claims.

10 We claim:

1. The method of making a shaped coat hanger from a one-piece block of rectangular cross section having broad and narrow side surfaces and having oblique end surfaces, which comprises the steps of separating the block into two complementary block halves by cutting said block at an angle substantially less than 90° to the plane of a broad surface along an S-shaped line which is curved at the ends and which begins and ends short of said oblique end surfaces, to provide block halves each having a curved surface whereof the elements are disposed substantially less than 90° with respect to said broad surfaces, and arranging said block halves with the oblique end surface of each block half in abutting relationship with the oblique end surface of the other.

25 2. The method of claim 1 which includes the step of shaping said block halves.

3. The method as claimed in claim 1 which includes the steps of shaping said block halves prior to said arranging step, then securing said block halves to each other when arranged, and sanding the arranged and secured block halves to provide a finished coat hanger body.

4. The method of claim 1 in which said angle is from 10° to 60°.

35 5. The method of claim 1 in which said angle is from 15° to 45°.

6. The method as claimed in claim 1 in which said curved surface is an S-shaped surface which is substantially symmetrical with respect to the longitudinal axis of said block.

40 7. The method as claimed in claim 6 in which the orthogonal projection of said curved surface upon one of said side surfaces is asymmetrical with respect to the longitudinal centerline of said surface.

45 8. The method as claimed in claim 6 in which the orthogonal projection of said curved surface falls primarily on said broad surface.

9. The method as claimed in claim 6 in which the orthogonal projection of said curved surface falls primarily on said narrow surface.
